MACHINE FOR TREATING REFUSE

Herbert T. Cobey, Galion, Ohio, assignor to Imco, Inc.

Filed July 24, 1969, Ser. No. 18,382

Term of patent 14 years

Int. Cl. D12—13

U.S. Cl. D14—3

Fig. 1.

Fig. 2.

Fig. 3.

Fig. 4.

Fig. 5.

FIG. 1 is a front elevational view of a machine for treating refuse showing my new design;

FIG. 2 is a rear view of the machine of FIG. 1;

FIG. 3 is a right side elevational view of the machine of FIG. 1;

FIG. 4 is a left side elevational view of the machine of FIG. 1; and

FIG. 5 is a top elevational view of the machine of FIG. 1.

In use, the machine for treating refuse comprises a wheeled frame for movement along windrows of refuse and a transverse rotary drum of engagement therewith.

I claim:

The ornamental design for a machine for treating refuse, as shown and described.
